ELECTRICAL APPARATUS

Royal Lee, Milwaukee, Wis.

Application November 30, 1942, Serial No. 467,335

8 Claims. (Cl. 171—242)

1

The present invention relates to electrical apparatus, and has for an object to provide an improved apparatus for electrically translating small mechanical displacements as in acoustics and gauging operations.

Another object is to provide an electrical translating device which is capable of producing relatively large variation in inductance with a comparatively small mechanical displacement.

A further object is to provide an improved microphone which is of simple and rugged construction and has a good response to impressed vibrations.

A still further object is to provide electrical apparatus which is so arranged as to form a simple and reliable dimension gauge.

The invention further consists in the several features hereinafter described and claimed.

In the accompanying drawings, illustrating certain embodiments of the invention,

Fig. 1 is a side elevation of a translating device incorporating features of the invention and arranged to form a microphone;

Fig. 2 is a sectional elevation taken generally along the line 2—2 of Fig. 1;

Fig. 3 is a sectional elevation taken generally along the line 3—3 of Fig. 2;

Fig. 4 is a sectional view taken generally along the line 4—4 of Fig. 3;

Fig. 5 is a detail sectional elevation taken generally along the line 5—5 of Fig. 3;

Fig. 6 is a detail view of a casing band of the device;

Fig. 7 is a diagrammatic view of an electrical system for the microphone;

Fig. 8 is an elevation of a modified form of microphone apparatus adapted for measuring or checking the surface finish of a work piece;

Fig. 9 is a front elevation of work-gauging apparatus arranged in accordance with the invention and adapted for gauging an opening in a work piece;

Fig. 10 is an enlarged sectional elevation of part of the work-gauging apparatus of Fig. 9;

Fig. 11 is a front elevation of a modified form of gauging apparatus adapted for gauging an external dimension of a work piece, and

Fig. 12 is a diagrammatic view of an electrical system for the gauging apparatus of Figs. 9 and 11.

Referring to Figs. 1 to 7 of the drawings, a microphone or signal translating device is designated generally by the numeral 15. The microphone includes coils 16 and 17 arranged in proximity to each other and relatively movable

5 to vary the coupling between them. These coils, which form a variable inductor, are preferably connected in series and are arranged differentially or in opposing relation. The coils are of the spirally wound flat or pancake type arranged side by side in coaxial relation and are preferably identical and of small size, usually considerably less than one inch in diameter. The coil spacing is small, being usually less than $\frac{1}{16}$ inch.

10 The microphone coils are mounted for relative vibratory movement as hereinafter described, and are connected in a suitable electrical system such as that of Fig. 7. In this system, the variable inductor consisting of the two coils 16 and 17 is connected across the input terminals of a detector or demodulator 18 and in some cases may be shunted by a small variable condenser 19. A high-frequency oscillator 20 of any suitable type, such as an electron-coupled type, impresses a high-frequency voltage on the input terminals of the detector. In some instances the oscillator may be crystal-controlled. The oscillator frequency is not critical and may be 15 selected from a wide range of values such as from 30 kilocycles per second to 500 kilocycles per second, although these are not to be regarded as limiting values. In general, the use of the higher frequencies is desirable as the microphone coils can then be made small and light. The tuned parallel input circuit of the detector, comprising the connected microphone coils and their shunting capacities, is set to a frequency 20 slightly above or below the oscillator frequency by adjusting the variable condenser 19 (or by adjusting the oscillator), so that the normal operating point of the detector is not at the crest of the resonance curve but lies on one of the sloping sides of the curve. The relative movement of the microphone coils under impressed mechanical vibrations changes the reactance of the detector input circuit, and thus produces a correspondingly modulated detector output. The detector output is amplified by a low-frequency 25 amplifier 21 and the resulting amplified signal is then applied to a recorder 22 or to a sound reproducer 23, or to both. In some instances a voltmeter 24, which may be of the vacuum tube type, is connected to the output terminals of the low-frequency amplifier. For some purposes as in radio transmitters, or in phonograph pickups, the modulated high-frequency output of the system can be utilized as such or in amplified form.

25 The relatively movable microphone coils 16

and 17 are mounted within a metal shielding casing comprising a cylindrical cup 25 closed at its end by a disk 26. A hook-shaped bracket 27 within the casing is rigidly secured to the end wall of the cup by screws 28. Two parallel studs 29 are riveted to the bracket and extend in the diametral plane of the cup 25 and parallel to the axis of the cup. A flat plate 30 of insulating material extends at right angles to the cup axis and has apertured end portions slidably supported on the reduced threaded ends of the studs, the plate ends being confined between nuts 31 on the studs and compressed coiled springs 32 surrounding the studs. The flat microphone coil 16 is secured to the plate, as by a suitable adhesive, and is substantially coaxial of the casing. By turning the nuts 31, the plate and attached coil can be axially adjusted in the casing.

Two spring arms 33, preferably in the form of leaf springs, are spaced from opposite sides of the coil-supporting plate 30 and extend substantially parallel to the plate. The leaf springs, which have the shape seen in Fig. 5, are each secured at one end to the bracket 27 as by screws 34, and each spring has its inner portions cut away to form a reentrant tongue 35 attached to the free end of the spring, thus increasing the effective length of the spring. A stem 36 of insulating material extends between the leaf springs along the axis of the casing and is rigidly secured at opposite ends to the apertured tongues 35 of the spaced springs, the stem extending through the apertured central portion of the coil-supporting plate 30. The end of the stem adjacent to the end wall of the cup 25 is fastened to the adjacent leaf spring by a nut 37, and the other end of the stem is fastened to the corresponding leaf spring by a screw threaded shank 38 formed on a flat damping disk 39. The damping disk, which also forms an inertia member, fits loosely within the cylindrical cup 25 out of contact therewith and lies adjacent and parallel to the casing disk 26 to define a shallow damping chamber 40. A flange or disk 41 of insulating material is secured to or formed on the stem 36 adjacent and parallel to the plate 30. The flat coil 17 is secured to the face of the disk 41 adjacent the coil 16, as by a suitable adhesive.

A microphone cable 42, preferably of the coaxial type, is suitably anchored on the bracket 27, as by a terminal-forming grommet 43, and has its terminals connected to the coils 16 and 17, the cable extending through an opening 44 in the casing cup 25. A pair of complementary cup-shaped housing members 45 of insulating material snugly enclose the casing 25, 26 and have registering notches 46 at their meeting edges to accommodate the cable. The cup-shaped housing members have enlarged rim portions 47 which are retained in assembled relation by a surrounding resilient metal band 48 with inturned marginal flanges 49. The ends of the band are provided with complementary halves of a screw-threaded sleeve 50 through which the cable passes, and the split band is held in clamped position by a collar nut 51 surrounding the sleeve. The ends of the housing members are crowned and a loop member 52 is secured to one of these ends to receive a strap or tape, not shown, by which the microphone may be secured to a vibration-transmitting surface. When the microphone is used for diagnostic work, in the manner of a stethoscope, the crowned end of the housing is placed against the body of a patient and the device is usually strapped or taped in position.

In operation, the vibrations of the source are transmitted to the contacting housing of the microphone, causing the housing and the parts of the device rigid therewith, including the coil 16, to vibrate in unison. The coil 17, however, which is supported by the leaf springs 33, tends to remain stationary because of the inertia of the damping disk 33 and other parts rigid with the coil 17, and the result is a relative vibration of the two coils in accordance with the impressed vibrations. The inductance of the associated coils 16 and 17 varies accordingly, decreasing as the coils move toward each other and increasing as they move apart. The varying inductance 10 changes the reactance of the detector input circuit which is connected to the constant frequency oscillator 20, thus producing a modulated detector output. The resulting signal is then amplified and applied to one or more of the output devices 15 22, 23 and 24.

By connecting the microphone coils in series opposing relation, a relatively large change in inductance is effected for a comparatively small change in the coil spacing, thus improving the 20 sensitivity of the device. The normal spacing of the coils is not critical, although the spacing has an optimum value which is readily determined by experiment. The coil spacing is adjusted by 25 turning the nuts 31, the springs 32 serving to retain the adjustment. As the microphone may be used in various positions between vertical and horizontal, the normal coil spacing may vary slightly. However, by making the circuit 30 adjustments with the microphone in about a 45° position, changes in the operating characteristics 35 will be minimized. The normal coil spacing is not affected by the contact between the microphone and vibration-transmitting surface.

As the operation of the microphone depends on 40 the relative position or coupling of the coils and not on the rate of change of coil displacement, the microphone is capable of responding to mechanical vibrations of relatively low frequency.

While the invention is here shown to be embodied in an inertia-type microphone, certain 45 features of the invention are also applicable to microphones of the diaphragm type.

The modified form of microphone apparatus 50 shown in Fig. 8 is adapted for measuring or checking the surface finish of a work piece. This apparatus includes a microphone or translating device 115 which is generally similar to the microphone 15 of Figs. 1 to 6 and is connected in a suitable electrical system such as that of Fig. 7. 55 In the modified microphone the coil 16 is stationary and the coil 17 is movable and is actuated by a plunger or stylus 153 having a hard, fine, rounded tracing tip 154 such as a diamond or sapphire. The damping and inertia member 38, 39 of Fig. 3 is omitted, and is replaced by a pin or stud 138 against which the inner end of the stylus abuts in coaxial relation to the coils, the microphone housing being centrally apertured to 60 pass the stud. The stylus is here shown to extend downwardly from the microphone housing, and passes through a centrally apertured flanged bushing 155 which is rigidly secured to the crowned end of the housing. The bushing is secured to a carriage 156 slidable on a guide member 157 in a direction at right angles to the stylus, the carriage being reciprocated as by 65 means of a link 158. The plunger is urged downwardly by a light coiled spring 159 surrounding the plunger. A work holder 160, mounted on a support 161 below the microphone, is adapted to 70 75

carry a work piece 162. In the case of a cylindrical work piece, such as a piston pin, the work holder may be in the form of a V-block.

In the operation of the device of Fig. 8, the tracing tip 154 of the stylus 153 is brought into contact with the work piece 162, and the microphone carriage is reciprocated, causing the stylus 153 to slide along the surface of the work piece. Any surface irregularities on the work piece will produce a vibration of the microphone coil 17, and will be made evident by one or more of the output devices 22, 23 and 24 of the system of Fig. 7. The recorder 22 and voltmeter 24 may be calibrated to indicate the extent of the surface irregularities. The microphone is here shown to be movable with respect to the work but it will be evident that this relation may be reversed.

The modified form of apparatus shown in Figs. 9 and 10 is adapted for gauging or checking dimensions of a work piece. This apparatus includes a translating device 215 generally similar to the microphone of Fig. 8, although the device is not used as a microphone but rather as a displacement indicator. The translating device 215 is secured in horizontal position to the underside of a bracket 263 mounted on a base 264. In this device the coil 17 is the movable coil and is arranged above the coil 16. A ring member 265 is mounted above the bracket 263 and is secured thereto by screws 266 which also serve to attach the translating device to the bracket. The movable coil is actuated by a vertical plunger 267 which bears at its lower end on the stud 138, the latter attaching the upper end of the coil-supporting stem 36 to the upper leaf spring 33, and the upper end of the translator housing being centrally apertured to pass the stud. The plunger is slidably mounted in a shouldered bore 268 formed in a cylindrical body member 269, the lower end of which is detachably secured in the ring member 265 by a set screw 270. The body member has a reduced cylindrical extension 271 at its upper end and is radially slotted to receive a bell-crank lever 272 which is pivotally mounted to swing about a horizontal axis. The lever 272 has a vertical arm which projects upwardly into the cylindrical extension 271 and is provided with a rounded contact portion 273 projecting laterally from the extension, the projection of the contact portion being limited by an adjusting screw 274 engageable with the horizontal arm of the lever and disposed in the upper end of the bore 268. The plunger is urged upwardly by a light coiled spring 275 but the adjusting screw 274 prevents the plunger from losing contact with the stud 238 on the coil-supporting stem of the translating device. The cylindrical extension 271 is adapted to receive thereover an apertured work piece 262 the inner diameter of which is to be gauged by the apparatus, this diameter determining the angular position of the bell-crank lever 272 and thereby determining the relative position of the coils 16 and 17 of the translating device.

The translating device 215 is connected in a suitable electrical system such as that shown in Fig. 12. In this system a high-frequency oscillator 220, similar to the oscillator of Fig. 7, is coupled to the input circuits of a bridge type vacuum tube voltmeter including a pair of vacuum tubes 276 and 277, preferably of the beam power type. The input or grid circuit of the tube 276 includes the variable inductor 16, 17, of the translating device, and in some instances a small adjustable shunting condenser 278, and the input

or grid circuit of the tube 277 includes a coil 279 and a small adjustable shunting condenser 280. The input circuits of the tubes are coupled to the oscillator by small condensers 281, and are tuned to a frequency slightly above or below the oscillator frequency, as in the system of Fig. 7. The vacuum or thermionic tubes have a common cathode resistor 282, and the anodes or plates of the tubes are connected to a current source 283 through a center-tapped resistor 284, the ends of which are connected to the anodes. A direct-current milliammeter 285, which may be of the zero-center or zero-end type, is connected between the tube anodes and is suitably calibrated. In the case of an instrument movement of the zero-end type, the normal current through the instrument is adjusted to bring the pointer to the center of the scale, as by adjusting the condenser 280 or the center-tapped resistor 284. If the same current source is used to supply the oscillator, a tuned choke 286 is connected between the source and the oscillator. The oscillator and associated apparatus, including the milliammeter 285, are housed in a suitable casing 287 mounted on the base 264.

In the operation of the apparatus of Figs. 9, 10 and 12, the work piece 262 is slipped over the vertical extension 271 of the body member, causing the bell-crank lever 272 to turn slightly on its pivotal axis and to depress the plunger 267 which in turn moves the coil 17 closer to the coil 16, thereby changing the inductance of the connected coils. The reactance of the input circuit of the vacuum tube 276 is thus changed, causing the plate current of this tube to change and thereby altering the current flow through the milliammeter 285. The system of Fig. 12 is so adjusted that with a work piece having a bore of normal size the pointer of the milliammeter will be at the zero mark when the work piece is in gauging position. If the bore varies from normal size the meter pointer will come to rest at a position indicating oversize or undersize, as the case may be. By turning the work piece on the cylindrical extension 271 any eccentricities in the bore will cause changes in the pointer position.

The modified form of apparatus shown in Fig. 11 is adapted for gauging or checking the external dimension of a work piece, such as a cylindrical member 362, and is used in an electrical system such as that of Fig. 12. The apparatus includes a translating device generally similar to the devices of Figs. 8 and 9. The plunger or stylus of Fig. 8 is replaced by a plunger 353 which is urged in one direction by a coiled spring 359. The plunger is here shown to merely abut against the stud 138, but it will be obvious that the plunger may be rigidly attached to this stud in which event the spring 359 may be omitted. The mounting bushing 155 is secured to one leg of a U-shaped frame 388, and the other leg of the frame is provided with an anvil member 389 in the form of a micrometer head screw-threaded in the frame and aligned with the plunger 353.

In the operation of the device of Fig. 11, which is connected in the electrical system of Fig. 12, the work piece 362 is inserted between the anvil 389 and the plunger 353, causing displacement of the coil 17 towards the coil 16. This effects a deflection of the meter 285, as with the device of Fig. 9, thereby checking the diameter of the work piece. In some cases the inserted work piece may be turned to check any eccentricity.

Certain specific embodiments of the invention have been shown and described, but it will be un-

derstood that changes and modifications may be made therein within the spirit of the invention.

What I claim as new and desire to secure by Letters Patent is:

1. Electromechanical translating apparatus comprising a pair of approximately coaxial substantially flat spirally wound coils disposed side by side in closely spaced relation and adapted to be traversed by high-frequency current, said coils being connected differentially to each other and being relatively displaceable in an approximately axial direction to form a variable inductor, a vibratory supporting housing for said coils adapted to transmit mechanical vibrations to one of said coils, means for resiliently mounting the other coil in said housing, and inertia means for resisting movement of said last-named coil during the vibration of the housing.

2. Electromechanical translating apparatus comprising electromagnetically coupled coils adapted to be traversed by high-frequency current and relatively displaceable to vary the coupling thereof, a vibratory support for said coils adapted to transmit mechanical vibrations to one of said coils, means for resiliently mounting another of said coils on said support, and inertia means for resisting the movement of said last-named coil during the vibration of the support.

3. Electromechanical translating apparatus comprising electromagnetically coupled coils adapted to be traversed by high-frequency current and relatively displaceable to vary the coupling thereof, a vibratory support for said coils adapted to transmit mechanical vibrations to one of said coils, means for resiliently mounting another of said coils on said support, and a damping member secured to said last-named coil and forming a damping chamber with said support.

4. Electromechanical translating apparatus comprising electromagnetically coupled coils adapted to be traversed by high-frequency current and relatively displaceable to vary the coupling thereof, a vibratory supporting housing for said coils adapted to transmit mechanical vibrations to one of said coils, means for resiliently mounting another of said coils in said housing, and an inertia plate secured to said last-named coil and forming a damping chamber with said housing.

5. Electromechanical translating apparatus comprising electromagnetically coupled coils adapted to be traversed by high-frequency current and relatively displaceable to vary the coupling thereof, a vibratory enclosing support for said coils adapted to transmit mechanical vibrations to one of said coils, and a pair of spaced spring arms secured to said support for resiliently mounting another of said coils.

6. Electromechanical translating apparatus

comprising electromagnetically coupled coils adapted to be traversed by high-frequency current and relatively displaceable to vary the coupling thereof, a support for mounting one of said coils, and a pair of spaced spring arms secured to said support and spaced axially of another of said coils for resiliently mounting said last-named coil.

7. Electromechanical translating apparatus comprising electromagnetically coupled coils adapted to be traversed by high-frequency current and relatively displaceable to vary the coupling thereof, a support, a pair of spaced spring arms secured to said support, said coils being disposed between said spring arms, means for mounting one of said coils on said support, and means including a member connecting the deflectable portions of said spring arms for mounting another of said coils.

8. Electromechanical translating apparatus comprising electromagnetically coupled coils adapted to be traversed by high-frequency current and relatively displaceable to vary the coupling thereof, a support having parallel studs, a carrier member for one of said coils slidable on said studs, coiled springs on said studs for urging said carrier member in one direction, screw-threaded members engaging said studs and forming adjustable stops for the carrier member to vary the position of the associated coil, and resilient means for supporting the other coil.
